REVERSIBLE FAN

Kenton D. McMahan, Schenectady, N. Y., assignor to General Electric Company, a corporation of New York

Application August 12, 1937; Serial No. 158,690

12 Claims. (Cl. 230—133)

The present invention relates to reversible centrifugal fans.

In centrifugal fans the air is discharged radially from the blades into a passage called a scroll which increases in area around the fan in its direction of rotation toward the outlet. A scroll designed for efficient operation with one direction of fan rotation will have a very low efficiency when the fan is operated in the reverse direction.

The object of my invention is to provide an improved construction and arrangement in casings for centrifugal fans in which the shape of scroll may be readily altered in accordance with the direction of rotation of the fan to produce efficient operation in both directions of rotation. For a consideration of what I believe to be novel and my invention, attention is directed to the accompanying description and the claims appended thereto.

In the accompanying drawing, Figure 1 is a sectional end elevation of a centrifugal fan embodying my invention, the parts being in the position for counterclockwise rotation of the fan; and Figure 2 is a view similar to Figure 1, the parts being in the position for clockwise rotation of the fan.

Referring to the drawing, the fan housing comprises spaced end walls 1, only one of which is shown, which are connected around their edges by peripheral walls 2. The walls 2 are symmetrical about a vertical axis extending through the center of the fan casing. Extending transversely between the walls 1 at the upper end of the fan casing is wall 3 which divides the casing into outlet passages 4 and 5. Within the casing is a fan 6 which comprises blades 7 connected at one end to a ring 8 and at the other end to disk 9. The disk 9 is fixed to a hub 10, in turn fixed to a drive shaft 11. During the operation of the fan air is admitted axially to the inner ends 12 of the blades through an inlet opening (not shown) and is discharged radially from the outer ends 13 of the blades. The walls 1 and 2 of the fan casing provide a passage around the fan into which the fan discharges, the passage leading to outlets 4 and 5. The shape of this passage is not suited for efficient operation of the fan in either direction. Extending transversely between the walls 1 within the peripheral walls 2 is a flexible wall 14 which may be made of suitable material, for example, a band of spring steel. Being located wholly within the passage defined by the casing walls, leakage between the edges of the wall 14 and the walls 1 is not im-

portant and packing is not required. Of course if such packing were supplied, the outer wall 2 would be eliminated. The midpoint of the wall 14 is hinged at 15 to the fan casing. The ends of the band are pivoted to lugs 16 and 17 which are fixed to a control rod 18 slidably carried in a bearing 19 in the wall 3. Upon reciprocation of the control rod, the flexible wall 14 is moved transversely to its face laterally or radially toward and away from the fan. The right end 10 of the rod 18 slidably projects outside the fan casing through a bearing 20 in the wall 2 and the projecting end of the rod is provided with a handle 21. When the rod is in the position shown in Figure 2, the left end of the rod fits in a socket 22 in the wall 2.

The contour of the flexible wall 14 is determined by stops, such as pins 23 and 24 carried by walls 1, which respectively engage the inner and outer surfaces of the band in accordance with the position of the rod 18. When the rod 18 is in the position shown in Figure 1 the outer surfaces of the portion of the wall 14 to the right of the pivot 15 engages the pins 24 and the inner surface of the portion of the wall to the left of the pivot 15 engages the pins 23. The left end of the wall 14 is adjacent the edge 25 of a cutoff 26 integral with the wall 3. The pins 23 and 24 are so located that the wall 14 provides a scroll or passage around the fan blades which gradually increases in area from the cutoff 26 around the fan in a counterclockwise direction toward the outlet 4. In this position the fan will operate efficiently when rotated in a counterclockwise direction and will discharge air through the outlet 4. The edge 27 of the cutoff 26 provides a dam directing the air to the outlet 4. The upper surface 28 of the edge 27 is inclined toward the wall 3 to assist in directing the air through the outlet 4.

When the control rod 18 is in the position shown in Figure 2 the inner surface of the portion of the wall 14 to the right of the pivot 15 engages the pins 23 and the outer surface of the portion of the wall to the left of the pivot 15 engages the pins 24. In this position the right end of the wall 14 is adjacent the edge 27 of the cutoff 26 and the left end of the wall is adjacent the wall 2 of the casing. The wall 14 now provides a scroll or passage around the fan blades which increases in area from the cutoff 26 around the fan in a clockwise direction toward the outlet 5. In this position the fan will operate efficiently when rotated in a clockwise direction and will discharge air through the outlet 5. The edge 25

of the cutoff serves as a dam directing air to the outlet 5, the upper surface 28 thereof being inclined toward the wall 3 to assist in directing the air.

5. The use of a flexible band or wall for changing the shape of the scroll in accordance with the direction of rotation of the fan permits a more efficient scroll since the band is free to flex and assume any desired position. In this 10 connection it will be noted that each end of the band 14 is straight or curved in accordance with the position of the control rod 18. Although I have shown the control rod as manually operated, it is obvious that the control rod could be 15 power-operated if desired and that other suitable operating mechanism could be substituted for the control rod.

What I claim as new and desire to secure by Letters Patent of the United States is:

20. 1. In a reversible centrifugal fan, a fan casing having a wall defining a passage around and spaced from the fan into which the fan discharges, said passage leading to an outlet, flexible walls at all times within said casing walls for changing the area of said passage, means 25 engaging a portion of said flexible walls for moving the flexible walls transverse to the faces thereof, and stops engaging other portions of the flexible walls for determining the position thereof whereby said passage increases in area 30 around the fan toward the outlet in the direction of rotation of the fan.

35. 2. In a reversible centrifugal fan, a fan casing having spaced end walls and a connecting peripheral wall defining a passage around and spaced from the periphery of the fan into which the fan discharges, said passage leading to an outlet, a flexible wall within the casing walls extending transversely across said spaced walls, means pivoting said flexible wall on the casing 40 intermediate its ends, means engaging the ends of said flexible walls for moving the walls toward and away from the periphery of the fan, and stops engaging an intermediate portion of the flexible walls for limiting the movement 45 thereof whereby the passage increases in area around the fan toward the outlet in the direction of rotation of the fan.

50. 3. In a reversible centrifugal fan, a fan casing having spaced end walls and a connecting peripheral wall defining a passage around the fan into which the fan discharges, a cut-off intermediate the ends of said peripheral wall defining therewith a pair of outlets, walls within said casing walls on each side of said cut-off 55 movable transversely to the faces thereof toward and away from said cut-off to change the area of said passage whereby the passage increases in area around the fan toward one of said outlets in the direction of rotation of the fan.

60. 4. In a reversible centrifugal fan, a fan casing having spaced end walls and a connecting peripheral wall defining a passage around the fan into which the fan discharges, said passage leading to an outlet, a flexible wall within the casing walls extending transversely across said spaced 65 walls and movable toward and away from the fan to change the area of said passage, means pivoting said flexible wall on said casing intermediate its ends, means engaging the ends of said flexible wall for moving the wall to change the area of said passage, and stops engaging intermediate portions of said wall for limiting the movement thereof.

70. 5. In a reversible centrifugal fan, a fan casing

having spaced end walls and a connecting peripheral wall defining a passage around the fan into which the fan discharges, a cut-off intermediate the ends of said peripheral wall defining therewith a pair of outlets, a flexible wall extending transversely of said end walls for varying the area of said passage, the ends of said flexible wall being on opposite sides of said cut-off and being movable transverse to the face of said wall toward and away from said cut-off. 10

6. In a reversible centrifugal fan, a fan casing having spaced end walls and a connecting peripheral wall defining a passage around the fan into which the fan discharges, a cut-off intermediate the ends of said peripheral wall defining therewith a pair of outlets, a flexible wall extending transversely between said end walls for varying the area of said passage, the ends thereof being on opposite sides of said cut-off and being movable transverse to the face of said wall toward and away from said cut-off, and stops engaging an intermediate portion of said flexible wall for limiting the movement thereof whereby said passage increases in area around the fan toward the outlet in the direction of rotation of 25 the fan.

7. In a reversible centrifugal fan, a fan casing having spaced end walls and a connecting peripheral wall defining a passage around the fan into which the fan discharges, a cut-off intermediate the ends of said peripheral wall defining therewith a pair of outlets, a flexible wall extending transversely between said end walls for varying the area of said passage, the ends thereof being on opposite sides of said cut-off and being movable toward and away from said cut-off, and stops engaging an intermediate portion of said flexible wall for limiting the movement thereof whereby said passage increases in area around the fan toward the outlet in the direction of rotation of 30 the fan.

8. In a reversible centrifugal fan, a fan casing having walls defining a passage around the fan into which the fan discharges, a cutoff in said passage having faces defining a pair of discharge 45 passages, movable walls in said passages facing the cutoff and movable toward and away from the faces of the cutoff for selectively changing the area of said discharge passages.

9. In a reversible centrifugal fan, a bladed 50 centrifugal impeller, a casing having walls around and spaced from the impeller defining a passage to which the impeller discharges, said passage leading to an outlet, movable walls wholly within the casing walls and spaced from 55 the impeller blades and forming at least one wall of said passage to which the impeller discharges, means for mounting the movable walls for shifting movement wholly within the casing walls and relative to the casing and to the impeller blades between positions corresponding to the direction of rotation of the impeller whereby the passage increases in area around the impeller toward the outlet in the direction of rotation of the impeller, and means for moving 60 65 said movable walls.

10. In a reversible centrifugal fan, a bladed 70 centrifugal impeller, a casing having walls around and spaced from the impeller defining a passage to which the impeller discharges, said 70 passage leading to an outlet, flexible walls wholly within said casing walls and movable therein by flexing transverse to the faces thereof to change the area of said passage, and means for flexing said walls to positions in which said pas- 75

sage increases in area around the impeller in the direction of rotation toward the outlet.

11. In a reversible centrifugal fan, a bladed centrifugal impeller, a casing, movable walls cooperating with the casing walls to provide a passage around the impeller and spaced therefrom to which the impeller discharges, said passage leading to an outlet, and means for moving said movable walls transversely to the face thereof to change the area of said passage whereby the passage increases in area around the impeller in its direction of rotation toward the outlet.

12. In a reversible centrifugal fan, a bladed

centrifugal impeller, a casing having spaced end walls, movable walls spaced from the periphery of the impeller and extending transversely between said spaced walls and cooperating therewith to form a passage around and spaced from the impeller to which the impeller discharges, said passage leading to an outlet, and means for moving said movable walls radially toward and away from the periphery of the impeller to change the area of said passage whereby it increases in area around the impeller in its direction of rotation toward the outlet.
